(57)

CLAIM

The ornamental design for a lid for beverage container, as shown and described.

DESCRIPTION

FIG. 1 is a top perspective view of a lid for beverage container showing our new design.

FIG. 2 is a bottom perspective view thereof.

FIG. 3 is a front elevational view thereof.

FIG. 4 is a left side elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines depict portions of the lid for beverage container that form no part of the claimed design.

1 Claim, 8 Drawing Sheets# US D1,016,555 S
